(57) **CLAIM**

The ornamental design for a configurable divider, as shown and described.

DESCRIPTION

FIG. 1 is a perspective view of a configurable divider in an unfolded configuration.

FIG. 2 is a top view of the configurable divider in an unfolded configuration.

FIG. 3 is a bottom view thereof;

FIG. 4 is a front view thereof;

FIG. 5 is a back view thereof;

FIG. 6 is a right-side view thereof;

FIG. 7 is a left-side view thereof;

FIG. 8 is a perspective view of the configurable divider in a partially folded configuration within a display case; and,

FIG. 9 is a perspective view of the configurable divider in a folded configuration within a display case.

The broken lines showing of a display case in FIGS. 8 and 9 illustrate environmental structure. All other broken lines represent portions of the configurable divider. The broken lines form no part of the claimed design.
